CLAIM

The ornamental design for a lawn lamp, as shown and described.

DESCRIPTION

FIG. 1 is a perspective view of a lawn lamp design showing my new design.

FIG. 2 is a front view of the lawn lamp.

FIG. 3 is a rear view of the lawn lamp.

FIG. 4 is a right side view of the lawn lamp.

FIG. 5 is a left side view of the lawn lamp.

FIG. 6 is a top view of the lawn lamp; and,

FIG. 7 is a bottom view of the lawn lamp.

The broken lines shown on the drawings depict portions of the lawn lamp that form no part of the claimed design.

Any shading and cross-hatching are not features of the design but are utilized to illustrate the surface contours of the lawn lamp design in the drawings.
